PIN CUSHION

Garvie J. Noe, 11300 St. Charles Rock Road,
Bridgeton, Mo.

Filed Feb. 1, 1966, Ser. No. 820

Term of patent 7 years

(Cl. D3—19)

FIG.1

FIG. 2

FIG.3

FIG.4

FIGURE 1 is a perspective view of a pin cushion embodying my new design;

I claim:

The ornamental design for a pin cushion, as shown and described.
